UNITED STATES PATENT OFFICE.

PAUL E. KLOPSTEG AND LESTER B. MANN, OF CHICAGO, ILLINOIS, ASSIGNEES TO
CENTRAL SCIENTIFIC COMPANY, OF CHICAGO, ILLINOIS, A CORPORATION OF
ILLINOIS.

APPARATUS FOR OBTAINING HIGH VACUA.

Application filed April 28, 1923. Serial No. 635,380.

To all whom it may concern:

Be it known that we, PAUL E. KLOPSTEG and LESTER B. MANN, citizens of the United States, and residents of Chicago, county of Cook, and State of Illinois, have invented certain new and useful Improvements in Apparatus for Obtaining High Vacua, of which the following is a specification and which are illustrated in the accompanying drawings, forming a part thereof.

This invention relates to high vacuum pumps of the vapor type. One of the characteristics of pumps of this type heretofore patented is high resistance in the passage or conduit leading from the source of vapor to the condenser, which has impaired the operation of the pump and increased the amount of heat required. The defect has generally been produced either by constriction or elongation of that passage or conduit, or by both constriction and elongation of that passage or conduit. One object of the invention is to eliminate this resistance and permit the vapor to be given a correspondingly high velocity between the source and the condenser.

Another characteristic of some pumps of this type heretofore patented has been the flow of condensed mercury, or other liquid through a portion of the passage or conduit for the gas to be exhausted. And it is another object of the invention to cause practically all the condensed liquid to return to the source of vapor through the conduit by which the vapor travels from the source.

Further objects and advantages of the invention will become apparent as the disclosure proceeds and the description is read in connection with the accompanying drawing illustrating selected embodiments of the invention, and in which—

Figs. 1 and 2 are longitudinal section and side elevation respectively of one form of pump made according to the invention;

Figs. 3 and 4 are sectional views taken on the lines 3—3 and 4—4 respectively of Fig. 1;

Figs. 5 and 6 are views similar to Figs. 1 and 2, illustrating another form of pump embodying the invention;

Fig. 7 is a sectional view taken on the line 7—7 of Fig. 5;

Figs. 8 and 9 are views similar to Figs. 1 and 2, illustrating a further modified form

of pump made according to the invention, and

Fig. 10 is a transverse sectional view taken on the line 10—10 of Fig. 8.

Referring to Figs. 1 and 2, the reference numeral 10 indicates a boiler or retort in which mercury, or other liquid, 11 is heated to produce vapor. The walls of the boiler are extended upwardly, as indicated at 12, to form a passage or conduit 13 discharging into a collecting chamber 14. It is not necessary that the conduit 13 have a cross sectional area equal to that of the boiler, but it is desirable and advantageous to have the conduit comparatively large and also quite short, for by this means vapor produced in the boiler passes to the collecting chamber 14 with a minimum of loss of speed and energy due to frictional resistance against the walls of the conduit. Consequently, the jet of vapor may be given such high speed that lateral motion of molecules of vapor becomes immaterial and this speed can be produced with a comparatively small amount of heat applied to the boiler.

For convenience in construction the walls 15 of the collecting chamber may be extended downwardly at 16 to surround the wall 12 of the conduit 13 and enclose an annular space 17, forming with the piping 18 a passage or conduit leading from the vessel to be exhausted.

The collecting chamber 14 is provided preferably at its upper portion with piping 19, leading to a supporting pump. A water jacket 20 may be placed about the collecting chamber and supplied with inlet and outlet piping 21 and 22, though other cooling means may be used if preferred.

In the operation of the pump the vapor condenses in the collecting chamber and descends in the form of liquid along the walls 15, returning to the boiler to be vaporized again. In order to prevent this liquid from entering the space 17 the walls 15 are provided with a constriction, or shoulder, 23 extending inward over the space 17 and forming a sort of leap from which the liquid passes into the conduit 13. The inner diameter of this shoulder or constriction is preferably not less than the inner diameter of the conduit 13 so that there is no obstruction of the movement of the vapor from the

boiler to the collecting chamber, but preferably the upper end of the conduit 13 is flared, as indicated at 24, to extend slightly beneath the shoulder or constriction. This 5 leaves the annular space 17 in open communication with the collecting chamber through an annular slit 25 which is protected from the descending liquid on its return to the boiler. It will be advantageous if the wall 10 12 of the conduit 13 is reversely curved, as indicated in Fig. 1, for in this way the conduit may be given a flaring mouth at the same time the passage for the gas to be exhausted will not embody any sharp corners 15 or the like, that would interfere with the diffusion of that gas.

However, a small amount of liquid will collect in the space 17 and since conduit 20 13 is short the lower portion of the space 17 will ordinarily be at a high temperature. It is, therefore, desirable to prevent vapor generated in this space from passing up the piping 18. By making the bottom portion 25 26 of the wall 16 inclined, as indicated in Fig. 1, liquid in the space 17 is made to run to the opposite side of the conduit from the piping 18 and consequently the bulk of any vapor generated will not reach that piping. Liquid thus collected passes 30 35 through a pin hole 27 back into the boiler. This pin hole can be conveniently made by drilling through the wall 16, as well as the wall 12, then plugging the hole in the wall 16.

35 The relationship between the generation of vapor and the size of the collecting chamber, with the efficiency of the cooling, limits the speed of the pump; for if vapor is generated more rapidly than it can be collected and condensed there will be back pressure 40 which will interfere with the diffusion of the gas into the jet. The proportions illustrated in the drawing give very efficient results, but greater speed can be had by enlarging the collecting chamber, which may be done by increasing the diameter or the length, or both.

45 The form of pump shown on Sheet 1 (Figs. 1, 2, 3 and 4) lends itself very readily to manufacture from metal, such as steel, and from non-metal, such as glass. All the parts can be made from standard tubing and the joints can be conveniently made by welding or fusing. In making the pump of steel the wall sections 26, 28 and 29 may be formed by laying a ring between the telescoping walls and fusing the ring to both walls.

50 In the pump shown in Figs. 5, 6 and 7, the boiler 30, conduit 31, collecting chamber 32, constriction 33, water jacket 34 and flaring mouth 35 are substantially the same as the corresponding parts shown on Sheet 1. The chief difference between the pumps is 55 in the conduit leading from the vessel to be exhausted. As shown in Figs. 5, 6 and 7,

this conduit encloses the collecting chamber and takes the form of a housing 36, which is reduced to convenient size piping at 37, leading to the vessel to be exhausted. The lower portion of the housing 36 is provided 70 with an integral flange 38 which is joined to the wall 39 corresponding to the wall 16 in Fig. 1. Above this joint the wall 39 is provided with a plurality of slots 40 which may be separated by offset portions 41 and in this way free communication is had between the annular space 42 and the housing 36 to permit the gas to be exhausted to diffuse into the jet.

75 The piping 43, 44 and 45 can be secured to the water jacket and the collecting chamber through relatively large openings in the housing 36, which are afterwards closed, as by welding or fusing disks to the walls of the housing.

80 The operation of this pump is substantially the same as that shown on Sheet 1, but it has the advantage of permitting the vessel to be exhausted to be conveniently supported directly above the pump.

85 In Figs. 8, 9 and 10 a modified construction is shown which, though easily made of steel, lends itself particularly to manufacture from glass. In this construction the boiler 46 and the conduit 47 are composed of one piece, similar in form to a test tube. The walls of the collecting chamber 48 are tubular and extend down around the conduit 47 to which they are secured by fusion 90 or the like at 49, somewhat below the end of the piping 50 which leads to the vessel to be exhausted. The collecting chamber is reduced at 51 and extended in tubing 52 leading to the supporting pump. The wall of the water jacket 53 telescopes with the wall 48 of the collecting chamber and is secured thereto at 54 and is closed by a plug, or cork, or the like at 55. The construction 56 and the flaring mouth 57 are similar to those 95 described in the other forms of pump.

100 As illustrated the boiler 46 and conduit 47 converge slightly towards the top, but this is not sufficient to materially reduce the efficiency of the pump, especially so when the length of the conduit 47 is kept small.

105 In all forms of the pump the water jacket or other cooling means does not extend down to the constriction or shoulder from which the condensed liquid leaps into the vapor 110 conduit.

115 This permits that portion of the walls 15 to become and remain heated, which results in two advantages in the operation of the pump. When the descending liquid comes in contact with the heated shoulder a slight amount of vapor is formed between the liquid and the wall, that acts as a lubricant promoting the leaping of the liquid from the shoulder, and molecules of vapor impinging against the underside of the

shoulder are prevented from collecting and running down into the annular space 17.

We claim as our invention:

1. In a high vacuum pump of the vapor type, a boiler, a collecting chamber above the boiler and provided with cooling means, a conduit between the boiler and collecting chamber and an inwardly extending projection above the upper end of the conduit 10 and lying in the path of liquid descending from the collecting chamber.
2. In a high vacuum pump of the vapor type, a boiler, a collecting chamber above the boiler and provided with cooling means, 15 a conduit leading from the boiler to the collecting chamber, a second conduit leading from the vessel to be exhausted to the collecting chamber at the same point as the first conduit and means for causing liquid descending from the collecting chamber to pass down the first conduit.
3. In a high vacuum pump of the vapor type, a boiler, a collecting chamber above the boiler and provided with cooling means, 25 a conduit leading from the boiler to the collecting chamber, a second conduit leading from the vessel to be exhausted to the collecting chamber at the same point as the first conduit, and a shoulder adjacent to the bottom of the collecting chamber overhang- 30 ing the outlet to the second conduit.
4. In a high vacuum pump of the vapor type, a boiler, a collecting chamber above the boiler, a conduit connecting the boiler with the chamber, a second conduit connected 35 with the vessel to be exhausted and terminated in an annular slit surrounding the first conduit and a constriction overhanging the annular slit and lying in the path of liquid passing from the collecting chamber 40 to the boiler.
5. In a high vacuum pump of the vapor type, a boiler, a collecting chamber above the boiler, a conduit connecting the boiler with the chamber, a second conduit connected 45 with the vessel to be exhausted, and including an annular passage surrounding the first conduit and having an inclined bottom in communication with the boiler.
6. In a high vacuum pump of the vapor 50 type, a boiler having its walls extended upwardly to form a conduit, a collecting chamber above the conduit having walls telescoping with the wall of the conduit and secured thereto, a constriction in the wall of the 55 collecting chamber above the end of the conduit and tubing connected with the outer of the telescoping walls and adapted to be in communication with the vessel to be exhausted.

PAUL E. KLOPSTEG.
LESTER B. MANN.
